UNITED STATES PATENT OFFICE.

GAYLARD W. DENYES AND OWEN SCHUTT, OF CASSOPOLIS, MICHIGAN.

SEEDER.

SPECIFICATION forming part of Letters Patent No. 726,880, dated May 5, 1903.

Application filed January 8, 1903. Serial No. 138,259. (No model.)

To all whom it may concern:

Be it known that we, GAYLARD W. DENYES and OWEN SCHUTT, of Cassopolis, Michigan, have invented a new and useful Improvement 5 in Seeders, of which the following is a specification.

Our improvement relates to the drag-bar of seeders, being particularly applicable to that kind which is provided with a parallel 10 or horizontal spring, and has to do with the means by which adjustment is secured between the spring and drag-bar to increase or decrease the tension of any individual spring at will.

15 Figure 1 is a perspective view of a drag-bar and shoe with a spring and operating-lever attached and our improvement in connection therewith. Fig. 2 may be considered a plan view of our invention, showing the operative relation of the spring-rod, the clip, and adjustable toothed side pieces. Fig. 3 is a sectional side elevation of the parts shown in Fig. 2 if cut on the line 3 3. Fig. 4 is a section of Fig. 2 on the line 4 4. Fig. 5 is a 20 plan of the grain-chute, showing the trunnions and link connecting with the spring. Fig. 6 is a transverse section on the line 6 6 of Fig. 1. Fig. 7 is a longitudinal section of same portion; and Fig. 8 is a side elevation 25 of a portion of Fig. 2, showing the teeth on the clip and on the slotted side piece.

Referring to the drawings, A represents the two-piece drag-bar; B, the furrow-opening device, shown as a shoe, secured to said drag-bar; C, the hollow standard or grain-chute; D, a spring-rod substantially parallel with the lower end of the drag-bar and shoe, and E a forked link engaging the upper end of the grain-tube C and connecting the free end of 30 the spring D with the rock-arm F, which is rigidly secured to the rock-shaft G.

The foregoing, generally considered, are parts common to many of the various styles of seeders, and a specific description is therefore unnecessary.

45 Between the opposing members of the drag-bar A is the clip H, pivotally secured thereto by the bolt h. This clip consists, essentially, of a boss, which forms the pivotal bearing 50 for the bolt h, and a downwardly-extending longitudinally-slotted web h', the lower end thereof merging into a semicircular rib ex-

tending transversely relative to the clip. The lower portion of this semicircular rib or boss is extended rearwardly, forming the lip 55 h⁴, which acts as a distance-piece between the two members of the drag-bar. On the boss of the clip are the shoulders h² h³, extending transversely relative to the length of said boss and forming a groove or seat for the 60 spring D, which lies therein, the spring D being beneath the said boss at this pivotal point and above the semicircular rib at the free end of said clip, as shown in Fig. 3. Integral with the semicircular rib are the projecting 65 lugs h⁵ h⁶, with teeth formed on the under sides thereof, as shown in Fig. 8.

J J are longitudinally-slotted side pieces, each provided on its upper edge with a ledge which fits over the edge of the drag-bar. On 70 each of these ledges is preferably a series of teeth adapted to be engaged by the teeth on the lugs h⁵ h⁶ of the clip H. The toothed surfaces of these ledges are correspondingly tapered, the teeth receding from the edges of 75 the drag-bar as they approach the pivotal bearing of the said clip, as shown in Fig. 3, and forming what amounts to a wedge serrated upon its upper edge. These side pieces are slotted, as shown in Figs. 1, 3, and 8, so 80 that as the bolt j, which secures them to the drag-bar, is loosened they can be moved longitudinally along the bar, thus bringing a higher or lower portion of the toothed wedge on the said side pieces to bear against the 85 toothed projecting lugs h⁵ h⁶ of the clip H, thus causing the said clip H to move upon its pivotal axis, which is formed by the bolt h. As this clip forms the bearing for the short end of the spring D and the fulcrum 90 of the spring is coincident with the pivotal point of said clip, any movement given the clip will accordingly affect the long end of the spring, moving it, if not restrained, to or from the shoe B, and if the movement of the said 95 spring is limited then what amounts to the equivalent will occur—i. e., the tension of the said spring will be increased or decreased, and the shoe B will be forced down to the soil with a greater or less degree of pressure. As 100 shown in the several figures, the side pieces J J are in their extreme upper positions, so that all adjustment will operate to increase the tension of said spring, since the strength

thereof is likely to decrease more or less from use. The connection between the spring D and the lifting device is such that the spring-pressure is exerted continuously on the shoe, 5 and the said shoe is limited in its vertical movement. This we accomplish by having the bent end of the link E forked, as shown in Fig. 5. This fork passes beneath the trunnions c c on the grain-tube C, and on the ends 10 of said fork are secured the rollers e e by the bolt e', as shown in Fig. 6. These rollers e e form a seat or pivotal bearing for the spring-rod D and are made in two parts, as shown, to facilitate construction and assembling. 15 The lifting mechanism brings this fork of the link E to bear against the trunnions c c and in this manner lifts the shoe or limits its downward movement.

The operation of our improvement is as follows: The long end of the spring D is held rigidly in position by the link E, the rock-arm F, and the rock-shaft G, with a suitable lever secured thereto. The short end of the 20 said spring D, bearing against the free end 25 of the clip H, which in turn presses against the bolt j, will exert a downward pressure upon the drag-bar and shoe; but the drag-bar being pivotally sustained at its forward end the rear or shoe end only will respond to 30 the action of the spring. It is thus seen that by movement of the rock-shaft A the shoes B can be pressed into the soil with any desired degree of pressure or by gravity alone. The pressure of each individual shoe is regulated 35 by loosening the bolt j, and to increase the effect of the spring the side pieces J J are moved downwardly along the drag-bar, the toothed wedges engaging at a higher point, thus raising the free end of the clip H and 40 the long end remaining in the same position. The pressure between the short end of the spring and clip will in consequence be increased. To decrease the spring-pressure,

the said slides are of course moved in the reverse direction.

What we claim as our invention, and desire to secure by Letters Patent, is—

1. In combination with the drag-bar of a seeder, an adjustable clip pivotally secured thereto, a spring fulcrumed on said drag-bar, 50 the pivotal point of said clip and the fulcrum-point of said spring being coincident, the spring consisting of a long arm extending approximately horizontally and connecting with the lifting and controlling device, and a short 55 arm bearing against said adjustable clip, a furrow-opening device secured to said drag-bar, a grain-chute secured to said furrow-opening device, and a lifting and controlling device pivotally connected with the free end 60 of the long arm of said spring and adapted to engage and raise the said grain-chute and connected parts thereof, substantially as described.

2. In combination with the drag-bar of a 65 seeder, a clip pivotally secured thereto, longitudinally - movable inclined - edged side pieces cooperatively connected with said drag-bar and clip, a spring fulcrumed on said drag-bar, said spring consisting of a long arm extending approximately horizontally and connecting 70 with the lifting and controlling device, and a short arm bearing against said clip, a furrow-opening device secured to said drag-bar, a grain-chute connected to said furrow-opening device, and a lifting and controlling device pivotally connected with the free end 75 of the long arm of said spring and adapted to raise the said grain-chute and connected parts thereof, substantially as de- 80 scribed.

G. W. DENYES.
OWEN SCHUTT.
